[57] CLAIM

The ornamental design for detachable handle for paint cans or the like, substantially as shown.

DESCRIPTION

FIG. 1 is an isometric of the detachable handle for paint cans or the like showing my new design;

FIG. 2 is a front view thereof;

FIG. 3 is a back view thereof;

FIG. 4 is a side elevational view taken from the left side of FIG. 1;

FIG. 5 is a top, plan view thereof; and

FIG. 6 is a bottom plan view thereof.
